UNITED STATES PATENT OFFICE.

FRANK CASEY, OF WASHINGTON, DISTRICT OF COLUMBIA, ASSIGNEE TO THE STONE STRAW COMPANY, OF WASHINGTON, DISTRICT OF COLUMBIA, A CORPORATION OF NEW JERSEY.

MANDEL.

1,255,134.

Specification of Letters Patent.

Patented Feb. 5, 1918.

Application filed February 28, 1916. Serial No. 80,892.

To all whom it may concern:

Be it known that I, FRANK CASEY, a citizen of the United States, residing at Washington, in the District of Columbia, have 5 invented certain new and useful Improvements in Mandrels, of which the following is a specification.

My invention relates to an improvement in mandrels employed in the manufacture of 10 paper tubes, such as artificial straws, and it embodies a means of lubrication at the point or approximately at the point on the surface of the mandrel where the spinning of the strips into tubes takes place, thereby reducing as much as possible frictional contact 15 between the tube and the mandrel.

It comprises a tube having ducts leading to the surface in connection with means for supplying these ducts with lubricant.

20 In the accompanying drawings:—

Figure 1 is a top plan view;

Fig. 2 is a longitudinal vertical sectional view on an enlarged scale, showing parts broken away; and

25 Fig. 3 is a section on the line 3—3 of Fig. 2 on a slightly enlarged scale.

The numeral 1 represents the mandrel. This is made of tubing, and has the ducts 2, 2, drilled therein to form outlets for the 30 lubricant, at or near the spinning-point of the tube or straw being made. The outer end of the mandrel is closed by a plug 3, the outer end of which plug forms the point 4 of the mandrel.

35 As a simple means of holding the mandrel in the stock 5, the inner end 6 is screw-threaded, and the nut 7 is screwed thereon, forming a head or enlargement which fits the bore of the stock at that point and affords a means of securing the mandrel 40 therein, as shown in Fig. 2.

After screwing this nut 7 on the threaded end 6 of the mandrel 1, the parts are assembled by inserting this end through the threaded bore 8 of the stock 5, after which 45 the cap 9 having a threaded tap 10 is slid over the mandrel, and the tap 10 is screwed into the threads 8, thus forcing the inner end of the mandrel with the nut 7 firmly against the shoulder 11 in the stock 5. Thus 50 a rigid connection between the mandrel and its stock is made, and a lateral support formed throughout a sufficient length of the mandrel to hold it in place and prevent undue vibration.

55 The oil is fed from an oil-cup (not shown) through channel 12 in the stock, and thence it finds its way through the hollow mandrel, and out with the required feed through ducts 2, 2, of which two are shown, although 60 more or less might be formed, accordingly as a greater or less surface is to be lubricated, or a greater or less quantity of lubricant is required in the formation of the tube or straw.

65 I claim:

A mandrel comprising a stock having a channel therein, and a bore at the outer end of the channel of larger diameter than the channel, thereby forming a shoulder at the 70 outer end thereof, a screw-threaded portion of still larger diameter than the bore at the extreme end of the stock, a tube having an enlarged inner end and a screw-threaded cap sleeved about the tube and engaging the 75 enlarged end thereof and having a screw-thread engagement with the stock whereby the enlarged end of the tube is held therein against the shoulder.

In testimony whereof I affix my signature. 80

FRANK CASEY.
